KNURLING TOOL

Joseph H. Boulet, Chicago, Ill.

Application September 14, 1948, Serial No. 49,171

2 Claims. (Cl. 80—5.1)

1

This invention relates to improvements in knurling tools, and is more particularly concerned with the provision of a knurling tool adapted for use in forming knurled surfaces on either large or small diameter stock.

In the use of knurling tools in a lathe, it has heretofore been the practice to urge the knurling rolls into contacting engagement against one side of the piece being knurled. On small diameter stock, it will be understood that the pressure exerted by the knurling rolls against one side of the stock tends to cause the stock to bend into bow-shape. It is, therefore, an object of this invention to provide a knurling tool in which the knurling rolls are adapted to be disposed to engage diametrically opposed sides of small diameter stock. When the knurling rolls are positioned on diametrically opposed sides of a piece of stock, they exert equal pressure from opposite sides of the stock and thus do not have a tendency to bend the stock out of its normal axial alignment.

It is a further object of this invention to provide a self-centering knurling tool adapted for use in a lathe for knurling surfaces on cylindrical stock of either large or small diameter.

It is a further object of this invention to provide a knurling tool suitable for use in a shaper or planer for knurling flat surfaces.

This invention embodies other novel features, details of construction and arrangement of parts which are hereinafter set forth in the specification and claims, and illustrated in the accompanying drawing wherein:

Fig. 1 is a side elevational view illustrating a knurling tool embodying features of my invention.

Fig. 2 is a front elevational view of same.

Fig. 3 is a top plan view of same.

Fig. 4 is a sectional view taken along the line 4—4 of Fig. 3, showing the position of the knurling rolls when positioned for knurling the surfaces of cylindrical stock.

Fig. 5 is a sectional view, corresponding to Fig. 4, showing the knurling rolls as positioned for knurling flat surfaces.

Fig. 6 is a transverse sectional view taken along the line 6—6 of Fig. 4.

Referring now to the drawing for a better understanding of this invention, the knurling tool is shown as comprising a sleeve-shape housing 6 formed with a top wall 7, bottom wall 8 and side walls 9—9. The housing 6 is preferably formed of one piece of metal to provide a rigid structure, but it is obvious that the housing may be formed of two or more pieces welded or otherwise secured together. A stock 11 is journaled for pivotal

2

movement intermediate its ends upon a pivot pin 12 which is mounted at its ends in apertures formed in the side walls 9—9 of the housing 6. The forward end of the stock, indicated at 13, is preferably formed with outwardly converging top and bottom walls 14 and 15, respectively. The forward end 13 of the stock is also formed with an aperture 16 to receive a compression spring 11.

A pair of roll supporting arms 18 and 19 are journaled at their inner ends upon pivot pins 21 and 22, respectively, which are mounted at their ends in apertures formed in the side walls 9—9 of the housing 6. The upper roll supporting arm 18 is disposed between the side walls 9—9 of the housing, adjacent the top wall 7; while the lower roll supporting arm 19 is disposed between the side walls 9—9 adjacent the bottom wall 8. The free ends of the roll supporting arms 18 and 19 are bifurcated at 23 and 24, respectively, to snugly receive knurling rolls 26 and 27, respectively. The knurling rolls 26 and 27 are journaled upon pins 28 and 29, respectively, provided on bifurcated free ends of the supporting arms 18 and 19.

The top wall 7 and bottom wall 8 of the housing 6 are provided with threaded apertures 31 and 32, respectively, to receive adjustment screws 33 and 34, respectively. Each adjustment screw is preferably provided with a locking nut 36.

The portion of the stock 11, indicated at 31, is adapted to be mounted within a tool holder 38 of a lathe in knurling the outer surface of cylindrical metal or other material mounted in a chuck or between the centers of a lathe. To adapt the knurling tool for use in standard lathes, the bottom surface 38 of the stock 11 is disposed approximately three-quarters of an inch from the axis of the pivot pin 12, as illustrated in Fig. 4, and the axis of the pivot pin 12 is adapted to be disposed in a horizontal plane with the axis of the cylindrical metal mounted in the lathe.

In knurling the surface of relatively large diameter metal, indicated in dotted outline at 39, the roll supporting arms 18 and 19 are preferably arranged in line contact engagement with the top and bottom walls, respectively, of the housing 6. The surface of the cylindrical piece 39 is knurled in the usual manner by first moving the knurling rolls 26 and 27 into engagement adjacent one end of the cylindrical metal 39 and then moving the lathe carriage parallel with the axis of the work.

In knurling the surface of relatively small diameter cylindrical metal, indicated in dotted outline at 41 in Fig. 4, the knurling rolls 26 and

27 are first positioned on diametrically opposed sides of the work and then moved toward each other to engage diametrically opposed sides of the work by means of the adjustment screws 33 and 34, respectively. It will be noted that the housing 6 is free to pivot relative to the stock 11 when the roll supporting arms 18 and 19 are disposed in an intermediate position between the top walls 7 and 8, respectively, and the portion 13 of the stock 11. The knurling tool is thus self-centering. In knurling relatively small diameter stock of, for example, one-eighth or one-quarter of an inch in diameter, it will be noted that the knurling tool does not exert a force tending to bend the work as the knurling rolls 26 and 27 are disposed on opposite sides of the work. To adapt the knurling tool for use in other types of machines, such as planers or shapers for forming a knurled surface on flat stock, indicated at 42 in Fig. 5 of the drawing, the forward portion 13 of the stock coats with the adjustment screws 33 and 34 to lock the roll supporting arms 18 and 19 and the housing 6 against movement relative to the stock 11. When the roll supporting arms 18 and 19 are disposed in their inner position in abutting engagement with opposite surfaces of the portion 13 of the stock 11, the knurling rolls 26 and 27 are in closely spaced relation and are each adapted to engage the flat surface of the work 42.

In order to assure a perfectly knurled surface on a piece of work, it is essential that the several parts of the knurling tool should not move laterally relative to each other. In applicant's construction, it is contemplated that the sides of the stock portion 13 and the sides of the roll supporting arms 18 and 19 should be in snug frictional engagement with the side walls 9-9 of the housing 6, and further that the side surfaces of the knurling rolls 26 and 27 should be finished for snug frictional engagement within the bifurcated portions 23 and 24 of the roll supporting arms 18 and 19.

After reviewing the specification and drawing, it will be apparent that the knurling tool thus shown and described is adapted for universal use in knurling surfaces on large or small diameter stock in a lathe, or in knurling flat surfaces on stock mounted in a planer or shaper. It will further be noted that the knurling tool is self-centering when employed in knurling cylindrical surfaces and may readily be adjusted to accommodate various types of work.

While this invention has been shown in but one form, it is obvious to those skilled in the art that it is not so limited but is susceptible of various changes and modifications without departing from the spirit and scope of the claimed invention.

I claim as my invention:

1. A knurling tool comprising a rigid, flat, end-wise, open sleeve-shaped housing having side walls and relatively narrow top and bottom walls, a shank to be engaged in the tool post of a machine having an end portion disposed within said housing medially of said top and bottom walls and snugly received between said side walls, said end portion being tapered from the rear housing opening to the front opening thereof and pivotally engaged adjacent said rear opening, a pair of

roll supporting arms disposed within said housing and snugly received between said side walls and pivotally engaged adjacent said rear opening and adapted to be successively pivotally moved into line contact with said tapered shank end portion and with the housing top and bottom walls, bifurcated end portions on the free ends of said arms extending outwardly of and in close proximity to the front opening of the housing and knurling rolls journaled therein, a compression spring mounted on the outer end of said tapered shank portion to yieldably resist movement of said roll supporting arms toward each other and to urge them towards the housing top and bottom walls respectively, and means extending through the top and bottom walls of the housing adjacent the front opening thereof for pivotally moving said arms towards each other and for bringing them into line contact and secure engagement with the tapered shank end portion.

2. A knurling tool comprising a rigid, flat, end-wise open sleeve-shaped housing having side walls and relatively narrow top and bottom walls, said side walls being recessed at their forward edges to define a shallow V between the end walls, a shank to be engaged in the tool post of a machine having an offset end portion disposed within said housing medially of said top and bottom walls and snugly received between said side walls pivotally engaged adjacent said rear opening and adapted to be successively pivotally moved into line contact with said tapered shank end portion and with the housing top and bottom walls, bifurcated end portions on the free ends of said arms extending outwardly of and in close proximity to the front opening of the housing and knurling rolls journaled therein, said bifurcated end portions being laterally offset and providing shoulders adapted to overlie and abut against the adjacent forward edges of top and bottom walls, a compression spring mounted on the outer end of said tapered shank portion to yieldably resist movement of said roll supporting arms toward each other and to urge them towards the housing top and bottom walls respectively, and means extending through the top and bottom walls of the housing adjacent the front opening thereof for pivotally moving said arms towards each other and for bringing them into line contact and secure engagement with the tapered shank end portion.
